UNITED STATES PATENT OFFICE.

CARLISLE A. LINCOLN, OF BUFFALO, NEW YORK, ASSIGNOR TO THE HOUDAILLE COMPANY, OF BUFFALO, NEW YORK, A CORPORATION OF DELAWARE.

CLIP FOR VEHICLE SPRINGS.

Application filed November 27, 1923. Serial No. 677,213.

To all whom it may concern:

Be it known that I, CARLISLE A. LINCOLN, a citizen of the United States, residing at Buffalo, in the county of Erie and State of New York, have invented certain new and useful Improvements in Clips for Vehicle Springs; and I do hereby declare the following to be a full, clear, and exact description of the invention, such as will enable others skilled in the art to which it appertains to make and use the same.

The present invention relates to an improvement in vehicle springs and more particularly to an improvement of this character designed to facilitate the application of spring covers or boots thereto.

The object of the present invention is to improve vehicle springs with a view to facilitating the application of projecting covers or boots thereto, the present form of spring permitting the employment of sectional casings between the spring clips without the necessity of causing the cover to extend over or about the clips.

With this object in view, the principal feature of the invention contemplates a simple and improved type of spring clip which is adapted for attachment to the adjacent ends of cover sections and which forms a seal or closure between the sections.

The new form of vehicle spring with the improved spring clip may be employed with the sectional spring cover shown and described in the copending application of applicants filed of even date herewith.

In the accompanying drawings illustrating the preferred form of the invention Fig. 1 represents a top plan view of a portion of a vehicle spring embodying the improved type of clip and with a cover attached thereto; Fig. 2 is a detail illustrating a side elevation partly in section of the spring shown in Fig. 1; Fig. 3 is a bottom plan view of the spring shown in Figs. 1 and 2 with the cover applied; Fig. 4 is a detail of the strap for securing the ends of the cover sections to the spring clip; and Fig. 5 is a detail illustrating one of the spacer members for insertion between the clip and the top face of a spring.

In the illustrated embodiment of the invention the spring is shown as provided

with a plurality of superimposed spring leaves 20 which are joined at points intermediate the center and ends of the spring by a clip indicated generally at 22. As shown more particularly in Figs. 1 to 3 of the drawings, the spring clip comprises a U-shaped yoke member 24 provided with relatively thin extensions 26 which extend in close proximity to the spring in opposite directions and about the sides and bottom of the spring, as indicated in the drawings. These extensions or flanges may be provided upon opposite edges with sealing ribs 28 for insuring a more effectual locking of the flexible sections to the clip. The clip is held in place by the usual cross bolt 30 which is surrounded by a tubular sleeve member 32 provided with oppositely extending flanges 34 which lie on the top of the spring between the opposite legs of the U-shaped yoke. These flanges are likewise provided with sealing ribs 36 and are maintained in spaced relation to the top of the spring through the provision of spacer members 38 of angle section, as indicated in Fig. 5, which are interposed between the flanges and the top face of the spring. It will be evident that with this construction the spring clip when assembled provides a flanged closure completely surrounding the spring throughout the area adjacent to the clip and adapted for attachment to spring cover sections. As indicated in Fig. 2, the flanged extension at one side of the yoke may be depressed to accommodate the end of an additional spring leaf, the spring clip being generally located at such a point that the end of a short leaf extends into proximity thereto.

The adjacent ends of the flexible cover sections may be conveniently secured to the extensions or flanges of the spring clip through flexible locking bands 39 riveted or otherwise secured to the ends of the cover sections and each provided with a locking tongue 40 adapted to engage with a slotted portion 42 to lock the end portion of the cover section securely about each flange, as indicated clearly in Figs. 1 and 3 of the drawings. When the cover section is secured in place by the locking band, the provision of the sealing rib serves to prevent the

cover from becoming disengaged from the flange through an endwise movement, due to the flexure of the spring.

The provision of vehicle springs provided with spring clips as above described permits the application of cover sections to enclose portions of the spring between the clips in a simple and convenient manner and without disassembling any portion of the 10 spring.

While it is preferred to employ the specific construction and arrangement of parts shown and described, it will be understood that this construction and arrangement is not essential except so far as specified in the claims 15 and may be changed or modified without departing from the broader features of the invention.

The invention having been described, what 20 is claimed is:

1. A clip for vehicle springs comprising, a yoke member surrounding the bottom and sides of the spring, a bolt connecting the top 25 ends of the yoke across the top of the spring, and a tubular sleeve surrounding the bolt

and having oppositely extending flanges of sufficient width to permit attachment of a flexible spring casing thereto.

2. A clip for vehicle springs comprising, a yoke and tie bolt for holding the leaves 30 of the spring in assembled relation, flanges extending in opposite directions from the yoke and surrounding the bottom and sides of the spring, and a tubular sleeve enclosing the bolt and having oppositely directed 35 flanges lying in proximity to the top of the spring, the flanges surrounding the spring being of sufficient width to provide engagement with a flexible spring casing.

3. A clip for vehicle springs comprising, 40 a yoke member surrounding the bottom and sides of the spring, a tie bolt extending across the top of the spring, a tubular sleeve enclosing the tie bolt having oppositely directed flanges, and means for maintaining 45 the sleeve in spaced relation to the top of the spring to provide a channel for the flow of lubricant thereunder.

CARLISLE A. LINCOLN.
